UNITED STATES PATENT OFFICE.

FRANK E. LEVANSELER, OF CHICAGO, ILLINOIS.

SUPPORT FOR HINGED COVERS OR MEMBERS.

1,207,946.

Specification of Letters Patent. Patented Dec. 12, 1916.

Application filed May 15, 1915. Serial No. 28,245.

To all whom it may concern:

Be it known that I, FRANK E. LEVANSELER, a citizen of the United States, residing at Chicago, in the county of Cook and State of Illinois, have invented certain new and useful Improvements in Supports for Hinged Covers or Members, of which the following is a specification.

This invention relates to certain new and useful improvements in means for supporting the hinged lids or covers of desks, trunks, boxes, pianos and the like, when raised or turned on their hinges to any desired elevation or angle, in such a manner that the supporting action or operation of the device will be automatic, and of such a character as to securely hold the lid, cover or member in its tilted, raised, or angular position against accidental lowering, falling or changing of the same, yet, so that, by the proper manipulation of the cover or member, and by applying slight pressure thereto, it can be easily lowered, closed or moved in the opposite direction.

The principal object of the present invention, is similar to that disclosed in my application for patent, Serial Number 13,821, filed March 11, 1915 for improvements in a support for hinged covers or members, that is to say, is to provide a support of the above named general character, which shall be extremely simple and inexpensive in construction, strong, durable and effective in operation, with its parts so made and arranged, that they can be easily applied or attached to the article and its cover or member, and when in use, will be concealed or protected, when the cover or member is closed.

Other objects and advantages of the invention will be disclosed in the subjoined description and explanation.

In the accompanying drawing, which serves to illustrate an embodiment of the invention, Figure 1 is a vertical sectional view through a portion of a box, trunk, or desk showing a portion of its lid or cover lifted to an angle, and illustrating by dotted lines the said lid or cover in its closed or lowered position, said view showing one form of the support, and Fig. 2 is a similar view of like parts, showing a modification in the construction of the support.

Like numerals of reference, refer to corresponding parts throughout the different views of the drawing.

Referring now to Fig. 1 of the drawing, the reference numeral 4 designates a portion of a box, trunk, desk, or the body of any receptacle that may be desired to close by means of a hinged lid or cover, which lid or cover is designated by the numeral 5 and is shown in the above named figure of the drawing, by continuous lines in an elevated or inclined position. The lid or cover 5 is shown as having a depending flange 6 at its perimeter, and as being secured by means of a hinge or hinges 7 to the upper rear portion of the box, desk, or trunk. If desired however, the depending flange 6 may be omitted and the member 5 secured by means of hinges directly to the body 4 of the trunk or other receptacle. Pivottally secured at one of its ends to the flange 6, when the same is used, is a link 8 which extends downwardly along one side of the end 9 of the box, and preferably within the same. Connected to the lower or free end of the link 8 is a spiral spring 10 which spring is adjustably connected at its other end by means of a hook 11 to a bracket 12 which bracket is secured to one side of the end 9 of the box or trunk, and preferably within the same, and at a point near the front upper corner thereof. The bracket 12 is provided with an apertured extension 13 at its end, adjacent to the link 8 and the screw-threaded stem 14 of the hook 11, is extended through said aperture and held in place by a nut 15 engaging said stem. By this means it is apparent that the hook 11 can be adjusted so as to regulate the tension of the spring 10 when desired. Pivottally secured at one of its ends, near the bracket 12 and between the same, and the link 8, is another link 16, which is shorter than the link 8, and has its other end pivotally connected to the link 8 between the ends of the latter, and by preference below the middle of the first named link.

In Fig. 2 of the drawing is shown a modification in the construction of the support which consists in reversing the positions of the bracket 12 and link 16, that is to say, in this modified construction, the bracket 12 is mounted on the trunk, or box 4, by preference on the inner surface of the end 9 thereof, rearwardly of the lower end of the link

8 which in this modified construction, is pivotally connected at its upper end to the flange 6 of the hinged member 5, when said flange is used. The spiral spring 10 connects the lower or free end of the link 8 in the modified construction to the bracket 12 in a similar manner to that first above described, and it will be apparent that the results obtained by the two constructions 10 will be similar.

From the foregoing and by reference to the drawing, it will be readily understood and clearly seen that by raising the lid or member 5 from the dotted line position 15 shown in the drawing, to that illustrated by continuous lines, the links 8 and 16 will be moved upwardly, from their dotted line positions, to those shown in the continuous lines in which positions the parts will be held or fixed, by reason of the tension of 20 the spring 10 on the lower end of the line 8 which is fulcrumed as at 17 on the link 16, which link will afford a shifting fulcrum as is obvious, so that no matter to what degree 25 the lid or member 8 may be raised from its closed or horizontal position, it will be fixedly held in such a position until it is desired to lower the same, when, by a very slight downward pressure on the lid or member 30 is applied, the same may be lowered gradually until it rests on top of the box, trunk or desk in which position it will remain until again lifted. It is evident that the flange 6 of the lid or member 5 may be omitted and that the link 8 can be pivotally secured thereto in any suitable manner. 35

Having thus fully described my invention, what I claim as new and desire to secure by Letters Patent is—

40 1. In a support for hinged covers or members, the combination with a hinged cover or member, of a link pivotally connected

thereto at one of its ends at a suitable distance from the hinged portion of the cover or member, a shifting fulcrum link pivotally connected at one of its ends to the first named link between the ends thereof and pivotally supported near its other end, and a spring connected at one of its ends to the free portion of the first named link and 50 at its other end to a suitable support.

2. In a support for hinged covers or members, the combination with a hinged cover or member, of a link pivotally connected thereto at one of its ends at a suitable distance 55 from the hinged portion of the cover or member, a shifting fulcrum link pivotally connected at one of its ends to the first named link near the free end of the latter and pivotally connected at its other end to a 60 suitable support, a spring connected to the free portion of the first named link, and means for adjustably connecting the other end of said spring to a suitable support.

3. In a support for hinged covers or members, the combination with a hinged cover or member, of a link pivotally connected thereto at one of its ends at a suitable distance 65 from the hinged portion of the cover or member, a shifting fulcrum-link pivotally 70 connected at one of its ends to the first named link between the ends thereof and pivotally supported near its other end, and a spring connected at one of its ends to the free portion of the first named link and at 75 its other end to a suitable support, the said links and spring being arranged with such angularity with respect to each other and to the hinged cover or support as to permit the latter to remain closed.

FRANK E. LEVANSELER.
